UNITED STATES PATENT OFFICE.

ALBERT J. HODGSON, OF PALMYRA, WISCONSIN, ASSIGNOR OF TWO-THIRDS
TO REES W. DUGAN AND BRADFORD SHINKLE, OF COVINGTON, KEN-
TUCKY.

STEAM-BOILER FURNACE.

SPECIFICATION forming part of Letters Patent No. 522,059, dated June 26, 1894.

Application filed January 20, 1894. Serial No. 497,475. (No model.)

To all whom it may concern:

Be it known that I, ALBERT J. HODGSON, a citizen of the United States, and a resident of Palmyra, in the county of Jefferson and State 5 of Wisconsin, have invented certain new and useful Improvements in Steam-Boiler Furnaces, of which the following is a specification.

My invention relates to an improved stationary boiler furnace for burning locomotive 10 sparks or other low grade of fuel that it has been found impracticable to burn successfully in furnaces of ordinary construction.

To this end my invention consists in providing a furnace closed against the admission 15 of air except through a blast pipe discharging under the grate bars, in providing means to keep the grate bars free from clinkers and to provide for cleansing the ash pit without necessitating the opening of the front of the 20 furnace.

The invention will be first fully described in connection with the accompanying drawings and then particularly referred to and pointed out in the claims.

25 Referring to the drawings, in which like parts are represented by similar reference letters wherever they occur throughout the various views: Figure 1 is a longitudinal vertical section of a steam boiler furnace constructed according to my invention. Fig. 2 30 is a horizontal section of the same taken through line $\alpha\alpha$ of Fig. 1.

The side and rear walls of the furnace may be constructed in any approved manner and 35 the furnace A and the boiler B supported therein in the usual manner. The bridge wall A' has its forward end sloping down at an angle from the passage between the boiler and bridge wall and the ash pit C.

40 D is a water pipe perforated on the under side and extending across the sloping front of the bridge wall underneath the grate bars E, for the purpose of washing the ashes that may fall upon the inclined front of the bridge wall 45 into the ash pit and out through the discharge pipe leading from the bottom of the pit, so that it is rarely necessary to open the front sliding doors c of the ash pit.

The essential feature of the invention is to 50 keep the ash pit and the space underneath

the grate bars closed to the admission of air, except through the blast pipe F, which extends through the rear wall of the furnace and through the bridge wall to the space under the grate bars, where it connects with the 55 branch F', which extends entirely across the space under the grate bars and is perforated or slotted upon the upper side to force the blast of air through a blower (not shown) directly up and through the spaces between the 60 grate bars, the air being partially heated in its passage through the pipe F and its branch F'.

To free the grate bars from clinkers, I have provided a transverse rock shaft G, which is journaled in bearings fixed in the sides of the 65 furnace walls. On this shaft are fixed collars g, which carry blades g' projecting alternately from opposite sides of the shaft and arranged to pass up through the openings between the grate bars when the shaft is rocked by the 70 rod H, which is connected to the downwardly projecting arm g², which arm is secured to the shaft. The end of the rod is provided with a handle h for the purpose of rocking the shaft by operating the rod back and forth, but in 75 place of this arrangement one end of the shaft may extend through the side of the furnace and be provided with a crank arm. In operation the blades g' throw the clinkers loose from the grate bars and can be readily removed from 80 the front of the furnace by the ordinary fire hook.

One great difficulty in all previous attempts to burn locomotive sparks was caused by the sparks clinking in flat sheets over the grate 85 bars and obstructing the passage of air through the fuel. By this means the grate bars are kept free allowing the air to pass up through the incandescent fuel upon the bars and causing perfect combustion.

In practice, I have found that the furnace as shown completely consumes the locomotive sparks without producing smoke, but if the fire has to be forced, a branch of the pipe F might extend up through the bridge wall so 95 as to supply the heated products of combustion, which pass over the bridge wall, with a supply of oxygen to produce perfect combustion. The uptake may also be provided, if necessary, with regulating dampers and the 100

fuel for the furnace is supplied in the usual way, through the fire doors, or may be fed by a mechanical stoker or hopper.

It is obvious that many mere mechanical changes may be made in the structure without departing from the spirit or scope of my invention, and, without limiting myself to the specific features shown and described, what I claim is—

10 1. In a steam boiler furnace, the combination of the grate bars, the closed chamber underneath the grate bars, the ash pit in front of said chamber, the bridge wall inclined from the rear of the grate bars forward to the 15 ash pit, and the blast pipe for delivering air under pressure into said chamber, substantially as shown and described.

20 2. The combination of the grate bars, the closed chamber underneath said bars, the bridge wall having inclined front, the ash pit below the inclined front of the bridge wall, the water pipe discharging over said inclined front, the discharge pipe leading from the ash pit, and the blast pipe to deliver air under 25 pressure below the grate bars.

25 3. In a steam boiler furnace, the combination of the grate bars, the closed chamber below said bars, the blast pipe to deliver air,

under pressure, into said chamber, and a transverse shaft provided with blades to pass 30 between the grate bars when the shaft is rotated or vibrated for the purpose of freeing said bars from clinkers, substantially as shown and described.

4. In a steam boiler furnace, the combination of the inclined bridge wall, the grate bars resting thereon and on the front of the furnace, the closed chamber underneath the grate bars, a perforated water pipe crossing the inclined front of the bridge wall near the grate 40 bars, the ash pit C having a discharge pipe leading from it, through which the ashes are carried by the flow of water from said water pipe, the blast pipe F leading from the rear of the furnace through the bridge wall and 45 connected to the transverse perforated branch F' for discharging air under pressure into the inclosed chamber, the rock shaft G having blades g' arranged thereon to pass between the grate bars, the arm g², the rod H to rock 50 said shaft substantially as and for the purpose set forth.

ALBERT J. HODGSON.
